UNITED STATES PATENT OFFICE.

WILLIAM H. GALVIN, OF SAN FRANCISCO, CALIFORNIA.

HOUSE LIGHT AND SIGN.

Application filed August 23, 1921. Serial No. 494,447.

To all whom it may concern:

Be it known that I, WILLIAM H. GALVIN, a citizen of the United States, and a resident of the city and county of San Francisco, State of California, have invented certain new and useful Improvements in House Lights and Signs, whereof the following is a specification.

This invention relates to a combined house 10 light and sign.

The object of the invention is to provide a lantern which will show an illuminated sign toward the street, in front of a house, and at the same time throw a light toward 15 the house, and illuminate the porch or vestibule or entrance door of the house.

In carrying out the invention I provide a three sided prismatic lantern, of which one side is preferably vertical and faced toward 20 the street, and displays the house number, or names of the street, or other pertinent legend, whilst of the other two sides, one faces backward and downward, so as to illuminate the porch or vestibule of the house 25 to which the apparatus is applied and the third side is simply a cover or lid and reflector through which the interior of the appliance may be conveniently reached. The interior of the lantern is provided with light 30 emitting means, such as, for example, an electric globe, and the front and rear faces may be provided with glass, tinted, or otherwise, and interchangeable to suit the color 35 or conditions and taste of the user.

The ends of the prism may also transmit light, and may be also provided with glass.

In the accompanying 1 sheet of drawing I have fully illustrated a lantern containing my invention in its preferred form.

40 In the sheet:

Figure 1 is a side elevation, showing a bracket in front of a building, with my improved lantern suspended therefrom.

Figure 2 is an enlarged elevation, showing the front or street face of the lantern.

Figure 3 is a cross-section, taken on the line 3, 3, of Figure 2, and shows the interior of my lantern.

Figure 4 is a section taken on the lines 4, 45 4, of Figure 3, looking in the direction of the arrows.

The front frame 1 of the lantern may extend up above the body of the same, and be perforated, as at 2 shown in Figure 2, for 50 bolts or screws to fasten it to the bracket 3, or other part of a building.

The frame 1 is provided with clips or angles 4 to hold a sheet 5, of glass, celluloid or other suitable material, on which may be delineated the legend desired, as seen, for example, in Figure 2, where the legend is the street and number, thus —102— Clay—.

If desired, one of the clips or angles 4 or both of them may be composed of springs or other convenient means adapted to removably secure the sheet 5 in position so that same can be easily interchanged for another one having a different legend.

Securely attached to the frame of the front 1, is the triangular frame of the rear 70 faces. This frame comprises side and end bars 6 and 7 shown in Figures 3 and 4, which are grooved at 8 and 9, to receive the edges of plates of glass 10 or other material, either plain or tinted as desired.

75 The top, or lid 11, of the lantern, preferably oblique as shown, and polished or coated so as to direct and reflect the same degree of light through the front face as well as the rear faces and is hinged, as at 12, to the front frame 1, and is provided at its opposite edge, with a catch 13, to engage the edge of the rear frame. At a convenient point in the top 11, one or more electric globes 14 may be secured, in such number as will furnish the desired degree of illumination. It is obvious that light from the globe 14 will be reflected by the lid 11 toward the front face as well as the rear face.

80 The legend on the front sheet 5 may be delineated on a sheet of glass, or may be cut or punched in an opaque sheet, which in that case may be integral with the frame, as seems preferable. And the glasses 10 in the 85 faces are removably secured in position so that they may be changed as often as desired, and may be varied as to tint or color, or design.

85 At its end edges the cover 11 may rest on frame bars 15, which brace the ends of the prism when in open form and connect the bars 6 with the front frame bars 16.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as 105 the same may be variously modified by a skilled mechanic without departing from 110

the spirit and scope of my invention as defined in the appended claims.

What I claim and desire to secure by Letters Patent of the United States, is the following, to wit:—

- 5 1. A house-front lantern, comprising a vertical front face adapted to bear a legend thereon, an oblique rear face adapted to expose a light therethrough, an oblique lid adapted to cover the space included between those members and a light secured to said oblique lid.
- 10 2. A house-front lantern, of three sided prismatic form, having a vertical front face, provided with means for attaching it to a support, and adapted to expose an illuminated legend toward the front, and an oblique rear face adapted to transmit light from the interior of the lantern, downward and backward, and an oblique cover adapted to enclose the interior space and reflect the lights through said faces.
- 15 3. A house-front lantern, of three sided prismatic form, comprising a vertical front face adapted to expose an illuminated legend toward the front, an oblique rear face adapted to transmit light, and a combined cover and reflector, adapted to reflect light from an interior source through both said faces.
- 20 4. A house-front lantern comprising a front face having a transparent sign plate, a triangular frame projecting rearwardly from each end of said front face, a bar connecting the edge of each frame, a frame supporting a transparent plate supported by the downwardly inclined rear edges of said triangular frames, and a cover resting on their upwardly inclined edges and provided with illuminating means on the under side.
- 25 40 5. A house-front lantern, comprising a front face, a frame projecting rearwardly, a cover for said frame, forming thereby a casing, a light in said casing and interchangeable transparent plates secured to said front face and frame adapted to transmit said light from said casing.
- 30 45 6. A house-front lantern, comprising a front face, frames projecting therefrom hav-

ing a plurality of open faces, a cover for said frames, transparent plates in said open faces, a light in said frames and means on said cover to reflect said light through said transparent plates.

7. A house-front lantern, comprising an open front face, a plate in said open front face having a sign thereon, a frame projecting from said open front face having a plurality of open faces, transparent plates in said faces of said frame, a light in said frame and means in said frame adapted to reflect said light therefrom.

8. A house-front lantern, comprising a front face having a legend thereon, a frame projecting from said front face having a plurality of faces, a plurality of transparent plates in each of said faces, a light in said frame and means to reflect said light through said plates and legend.

9. A house-front lantern, of three sided prismatic form, comprising a front frame, an oblique rear frame, said frames having a cover and a plurality of faces, interchangeable transparent plates in each of said faces and a light reflected from said cover through said faces.

10. A house-front lantern, comprising a front face having a legend thereon, a frame projecting from said front face having two lateral faces and a downward face of transparent material, a cover for said frame having a light globe projecting in said frame and means to reflect said light through said faces.

11. A house-front lantern, comprising a front face, a frame projecting therefrom provided with a plurality of open faces having transparent plates therein, a cover for said frame, a light globe secured to said cover and projecting in said frame and adapted to reflect the light through said faces.

In testimony that I claim the foregoing I have hereunto set my hand this 16th day of Aug., 1921.

WILLIAM H. GALVIN.
